UNITED STATES PATENT OFFICE.

CHARLES H. FOSTER, OF KANKAKEE, ILLINOIS, ASSIGNOR TO UNION SPECIAL MACHINE COMPANY, OF CHICAGO, ILLINOIS, A CORPORATION OF ILLINOIS.

THREAD-CUTTER FOR SEWING-MACHINES.

1,123,721.

Specification of Letters Patent.

Patented Jan. 5, 1915.

Application filed January 26, 1903. Serial No. 140,647.

To all whom it may concern:

Be it known that I, CHARLES H. FOSTER, a citizen of the United States, residing at Kankakee, in the county of Kankakee, State 5 of Illinois, have invented certain new and useful Improvements in Thread-Cutters for Sewing-Machines, of which the following is a description, reference being had to the accompanying drawing, and to the letters 10 and figures of reference marked thereon.

This invention relates to improvements in sewing apparatus, and particularly to apparatus for handling and sewing filled bags, and the object of the present invention is 15 to provide a cutting arrangement for cutting off the chain of stitches between the bags, which can be thrown into and out of operation by the operator, but the actual cutting and returning action of which shall be automatic. 20

The machine shown in the drawings is of the general type illustrated in my Patent, 875,339, granted December 31, 1907, and also contains features shown and described in 25 my prior Patent 875,513, granted December 31, 1907.

An object of the invention is to provide a cutting device for severing the chain of 30 stitches between stitched articles, which cutting device is operated by a continuously running member with connections between the same, and the cutter adapted to be manually controlled, whereby the cutter may be mechanically operated at any time 35 at the will of the operator.

A further object of the invention is to provide a device of the above character wherein the cutter may be operated to cut the stitches between stitched articles without stopping the action of the stitching 40 mechanism.

These and other objects will in part be obvious and will in part be hereinafter more fully disclosed.

45 The invention is illustrated in the accompanying drawings, in which—

Figure 1 is a side elevation of so much of an apparatus of the type referred to, as is necessary to a complete understanding of 50 my invention; Fig. 2 is a similar view of the preferred form of my invention which embodies the features of the form shown in Fig. 1, but includes certain additional features; Fig. 3 is a plan view of a portion of 55 the apparatus shown in Fig. 2; Fig. 4 is a

front elevation of the bracket to which the machine is secured; Fig. 5 is a sectional plan view of a portion of Fig. 3, and illustrating particularly the rod or pin for holding the lever out of engagement with the continuously running crank pin; Fig. 6 is a detail perspective view showing the sewing head with the cutter attached thereto. 60

Referring to the drawings, and particularly at first to Fig. 1, A represents the sewing machine, and 2 a pulley upon the shaft 3, journaled in bearings upon the bracket B, which supports the sewing machine. The sewing machine is of the usual construction and comprises a bed plate 50, an overhanging arm 51 in which vibrates a needle bar 52 carrying a needle 53. Upon this shaft 3 is fastened a disk 4, provided with a projecting pin 5, the shaft and disk being, of course, continuously operated from the constantly running part of the power transmitter, (not shown), which is belted to pulley 2. 70

So far as the cutter itself is concerned, the arrangement is substantially the same as 80 shown in my prior Patent 875,512, granted December 31, 1907, in which a pivoted lever 6, is adapted to engage the head of the knife supporting shafts, and press the knife C down against an anvil 7, supported upon the 85 lower end of the cylindrical bed plate of the sewing machine. From the upper end of the lever 6, which is pivoted in the goose neck, there projects horizontally a bar 8, which at its inner end passes through the 90 upper end of a vertical lever 10 pivoted at 11 to the machine frame. A head on the inner end of the rod or link 8, prevents said bar from being withdrawn through the vertical lever 10, and the seat for said bar 8 95 is formed, as shown in section in Fig. 2, to allow for movement of said vertical lever, on its pivot.

The upper end of the vertical lever is normally pressed outwardly by means of the 100 spring 12, the tension of which is regulated by the collar a, and the spring also acts to cushion the shock of the forward movement of the lever 10 after the cutting blow has been struck. Said vertical lever 10 at its 105 lower end is pivoted to a horizontal lever 13, which has a downwardly projecting part 14, to which is attached a spring 15, normally adapted to retain the same in the position shown in the right hand dotted lines. This 110

horizontal lever is provided at its outer end with a hardened steel piece *b*, (shown in Fig. 2), having a notch *c*, normally adapted to engage the pin 5 on the disk 4, 5 and beyond the projection forming the notch it slants upwardly and is adapted to be brought into engagement with a roller 16 on the bracket 17, whereby, as the end of the horizontal lever is moved outwardly by 10 the pin 5, it is swung on its pivot, and when the blow of the knife has been struck, is tripped out of engagement with the pin 5.

At its forward end, the horizontal lever is adapted to be engaged by a pin 20, which 15 is tripped by the bell crank lever 21, journaled on the bracket *B*. When the bell crank lever is moved to draw back the pin 20, the left hand end of the horizontal lever 13, through the action of the lower spring 20 15 is forced downwardly, so that its notch *c* engages the pin 5, said horizontal lever being drawn rearwardly, carrying also the lower end of the vertical lever 10, thus forcing the upper end of the vertical lever forward against the pressure of the spring 12, 25 and causing the knife to operate to cut the chain of stitches. After the knife has been actuated through the movement of the bar 13 by its connection with the pin 5, and released therefrom, the springs 12 and 15 quickly return the knife to normally raised 30 position and return also the bar 13 to the full line position shown in Fig. 1. The roller has forced up the outer end of the lever 13 and the pin 20 which has been released engages the upper surface of the lever and holds the same out of contact with the pin 5.

Figs. 2, 3, 4 and 5, represent a somewhat modified and preferable form of my 40 invention. In these figures, the form of the lever 13 is slightly different, and the arm 14 extends downwardly from the end thereof, the top of the lever being beveled, as 45 shown at *e*. The spring 15 is also differently attached, as shown.

A spring plunger 22, bearing in lugs 23 on the bracket, is set to have a limited movement by the jam nuts 24 and 25, and on the 50 return of the lever 10, after the blow has been struck, the shock is taken up by this spring plunger, which acts as a stop for the lever 10.

Instead of the tripping mechanism shown 55 in Fig. 1, a rod or pin 26 extending to the right hand side of the machine is provided, which is normally pressed outwardly by the spring 27 to engage the lever 13 and hold it out of engagement with the continuously 60 running crank pin. When this rod or pin 26 is withdrawn, the cutting operation takes place, and the springing back of the pin 26 to normal position restores the parts to inoperative position. This rod or pin, is controlled by the operator through the medium

of a pivoted lever 28, carrying on its inner end a pivoted spring dog 29, which, when the lever 28 attached to the rod 290 on the bracket 30, is swung to the left against the pressure of spring 31, bearing against the 70 collar 32 on the rod 290, forces the same to the right far enough to release lever 13. In this position the spring dog 29 slips by the collar 40 and allows the pin 26 to be immediately returned to its original position by 75 the spring 27, thus preventing the pin 26 being held long enough out of engagement with lever 13 to allow of a second or third operation to be given to the cutter mechanism, due to the rapid revolution of the 80 driving pin 5. Without this spring operated dog the operator could not return the pin 26 quickly enough to prevent duplicate blows being given to the cutter. This construction prevents duplicate blows of the 85 cutter, due to the operator not returning the trip lever to rest position soon enough to prevent a second and perhaps a third engagement, which would chop and mangle the chain.

The rod 290 is provided near its left hand end with a handle 33, so that the operator may trip the mechanism either with the right hand by manipulation of lever 28, or by manipulation of rod 290 with the left 90 hand. Furthermore, a chain leading over a pulley 34 may be attached to the lever 28 at one end, and at the other end to a foot treadle, so that the tripping lever may be operated by the foot of the operator, leaving 100 both hands free to manipulate the bag.

It will be understood that various minor modifications and changes may be made, without departing from the spirit of my invention.

Having thus described my invention, what I claim as new, and desire to secure by Letters Patent, is:—

1. An apparatus for sewing and cutting the connecting threads between stitched articles including in combination sewing mechanism, means for feeding the articles to be sewed thereto, a cutting device in rear of the sewing mechanism and operating across the line of feed to sever the stitching threads, and means for operating said cutting device without stopping the sewing mechanism including a continuously moving member with connections between the same and the cutting device, and manually controlled devices for throwing said connections into and out of connection.

2. An apparatus for sewing and cutting the connecting threads between stitched articles including in combination sewing mechanism, means for feeding the articles to be sewed thereto, a cutting device in rear of the sewing mechanism and operating across the line of feed to sever the stitching threads, yielding means for normally holding said 130

cutting device raised, a continuously moving device, a member connected with said cutting device and adapted to engage said continuously moving device for moving the cutting device to sever the threads, and manually controlled means for holding said member out of engagement with said continuously moving device, said continuously moving device being independent of the immediate driving device for the sewing mechanism whereby said cutter may be actuated without stopping the sewing mechanism.

3. In an apparatus for sewing filled bags and cutting the threads between the bags, a sewing mechanism and a cutting device, a continuously running member, a lever normally adapted to be engaged by the continuously moving member, connections between the lever and the cutting device, and means for holding the lever out of engagement with the continuously moving member; substantially as described.

4. In an apparatus for sewing filled bags and cutting the threads between the bags, a sewing mechanism and a cutting device, a continuously moving member, a lever normally adapted to be engaged by the continuously moving member, connections between the lever and the cutting device, and means for holding the lever out of engagement with the continuously moving member, and means for tripping the lever to cause it to be engaged by the continuously moving member; substantially as described.

35 5. In an apparatus for feeding and sewing filled bags, and severing the stitches between successive bags, the combination with a sewing mechanism, a feeding device for the bags, and a cutting device and a continuously moving member, a swinging lever normally adapted to be engaged by the continuously moving member, devices for holding the lever out of engagement with the continuously moving member, means for tripping the same, and connections between the lever and the cutting device, whereby when the holding devices are tripped the cutting device is operated; substantially as described.

50 6. In an apparatus for feeding and sewing filled bags, and severing the stitches between successive bags, the combination with a sewing mechanism, a feeding device for the bags, and a cutting device and a continuously moving member, a swinging lever normally adapted to be engaged by the continuously moving member, devices for holding the lever out of engagement with the continuously moving member, means for tripping the same, and connections between the lever and the cutting device, whereby when the holding devices are tripped the cutting device is operated, said connections including a vertical lever, and spring and lever connections between said vertical le-

ver and the cutter; substantially as described.

7. In an apparatus for feeding and sewing filled bags, and severing the stitches between successive bags, the combination with a sewing mechanism, a feeding device for the bags, and a cutting device and a continuously moving member, a swinging lever normally adapted to be engaged by the continuously moving member, devices for holding the lever out of engagement with the continuously moving member, means for tripping the same, connections between the lever and the cutting device, whereby when the holding devices are tripped the cutting device is operated, said connections including a vertical lever, and spring and lever connections between said vertical lever and the cutter, and means for adjusting the spring; substantially as described.

8. In an apparatus for feeding and sewing filled bags, and severing the stitches between successive bags, the combination with a sewing mechanism, a feeding device for the bags, and a cutting device and a continuously moving member, a swinging lever normally adapted to be engaged by the continuously moving member, devices for holding the lever out of engagement with the continuously moving member, means for tripping the same, connections between the lever and the cutting device, whereby when the holding devices are tripped the cutting device is operated, said connections including a vertical lever, connections between the same and the cutter, and a stop to limit the movement of the levers when they have been released; substantially as described.

9. In an apparatus for feeding and sewing filled bags, and severing the stitches between successive bags, the combination with a sewing mechanism, a feeding device for the bags, and a cutting device and a continuously moving member, a swinging lever normally adapted to be engaged by the continuously moving member, devices for holding the lever out of engagement with the continuously moving member, means for tripping the same, connections between the lever and the cutting device, whereby when the holding devices are tripped the cutting device is operated, said connections including a vertical lever, connections between the same and the cutter, and a cushioned stop to limit the movement of the levers when they have been released; substantially as described.

10. In an apparatus for feeding and sewing filled bags, and severing the stitches between successive bags, the combination with a sewing mechanism, a feeding device for the bags, and a cutting device and a continuously moving member, a swinging lever normally adapted to be engaged by the continuously moving member, devices for hold-

ing the lever out of engagement with the continuously moving member, means for tripping the same, connections between the lever and the cutting device, whereby when 5 the holding devices are tripped the cutting device is operated, said connections including a vertical lever, connections between the same and the cutter, and a cushioned stop to limit the movement of the levers when 10 they have been released, said cushioned stop comprising a spring pressed plunger with jam nuts for limiting its movement; substantially as described.

11. In an apparatus for feeding and sewing filled bags, and severing the stitches between successive bags, the combination with a sewing mechanism, a feeding device for the bags, and a cutting device and a continuously moving member, a lever normally 20 adapted to be engaged by the continuously moving member, a pin normally bearing against said lever, to hold it out of engagement with the continuously moving member, means for withdrawing said pin from 25 engagement with the lever, and connections between the lever and the cutting device; substantially as described.

12. In an apparatus for feeding and sewing filled bags, and severing the stitches between successive bags, the combination with a sewing mechanism, a feeding device for the bags, and a cutting device and a continuously moving member, a lever normally adapted to be engaged by the continuously 35 moving member, a pin normally bearing against said lever, to hold it out of engagement with the continuously moving member, means for withdrawing said pin from engagement with the lever, said means including a swinging lever, and means for operating it, and a yielding spring dog adapted to engage the pin and move it in one direction, but to yield under the pressure of the pin in the opposite direction, when the 40 swinging lever is retained in retracted position; substantially as described.

13. In an apparatus for feeding and sewing filled bags, and severing the stitches between successive bags, the combination with

a sewing mechanism, a feeding device for 50 the bags, and a cutting device and a continuously moving member, a lever normally adapted to be engaged by the continuously moving member, a pin normally bearing against said lever, to hold it out of engagement with the continuously moving member, means for withdrawing said pin from 55 engagement with the lever, a spring for automatically returning said pin, and connections between the lever and the cutting device; substantially as described.

14. In an apparatus for sewing filled sacks, the combination with a sewing mechanism and means for feeding the sacks thereto, a cutting device for severing the chain 65 of stitches, and means for operating the cutting device, including a continuously running crank, and connections between the same, and the cutter, and means for throwing the connections into and out of action; 70 substantially as described.

15. In an apparatus for sewing filled bags, a sewing mechanism, and means for feeding the sacks, in combination with a cutter, a continuously operating crank, a lever normally 75 adapted to be engaged by the crank, and connections between the lever and the cutter, and means for holding the lever out of engagement with the crank; substantially as described.

16. In an apparatus for sewing filled bags, a sewing mechanism, and means for feeding the sacks, in combination with a cutter, a continuously running disk having a pin thereon, a lever adapted to engage the pin, and be operated thereby to give the stroke to the cutter, means for holding the lever out of engagement with the pin, and means for automatically releasing the lever from the pin as the former moves, and connections between the lever and the cutter; substantially 85 as described.

In testimony whereof I affix my signature, in presence of two witnesses.

CHARLES H. FOSTER.
